SHOWER APPARATUS

Howard A. Mullett, Milwaukee, Wis., assignor to
 Bradley Washfountain Company, Milwaukee,
 Wis., a corporation of Wisconsin

Application April 26, 1939, Serial No. 270,093

2 Claims. (Cl. 4—145)

The invention relates to showers and more particularly to group showers.

In public institutions, large industrial plants of certain kinds, and in recreational centers group showers are used, and in some cases the amount of water used in these showers is considerable, and it, therefore, becomes desirable to prevent waste of water in the use of these showers. The object of the present invention is to provide an arrangement by which the supply of water to the shower is controlled by the bather, so that water is supplied to the shower only during the time the bather is using or desires to use the shower.

A further object of the invention is to provide a group shower arrangement in which each of the showers in the group has its water supply controlled by the bather, the controls being grouped about a central standard.

The invention further consists in the several features hereinafter set forth and more particularly defined by claims at the conclusion hereof.

In the drawings:

Fig. 1 is a vertical sectional view through a shower apparatus embodying the invention taken on the line 1—1 of Fig. 2, parts being broken away;

Fig. 2 is a plan view of the shower apparatus embodying the invention, parts being broken away;

Fig. 3 is a detailed sectional view taken on the line 3—3 of Fig. 2;

Fig. 4 is a detailed sectional view taken on the line 4—4 of Fig. 1;

Fig. 5 is a detailed sectional view taken on the line 5—5 of Fig. 2;

Fig. 6 is a detailed sectional view through the lower end of the apparatus showing the water supply coming from the bottom;

Fig. 7 is a detailed sectional view through the supply connections where the water comes from the bottom, parts being broken away.

Fig. 8 is a detailed sectional view taken on the line 8—8 of Fig. 1.

Referring to Figs. 1 to 5, inclusive, the shower apparatus is formed to provide a plurality of compartments 10 grouped about a central standard 11. The compartments 10 are formed by partitions 12 detachably secured to said central standard and to the posts 13 of an outer frame, which posts are secured together by tubing 14 and are secured to the standard 11 by radially disposed brace rods 15.

A shower head 16 is provided for each compartment which receives its water supply through a pipe 17 connected through a valve controlled passage with a supply head 18 which may be supplied with water either from above or below.

As herein shown the head 18 is mounted at the top of the central standard 11 which in-

cludes a plain tubing section 19 and a base fitting 20 having a tubular portion 21 and a flanged base 22 to which a drain pipe 23 is fitted. The tubing section 19 at its ends fits into sockets in said head 18 and base fitting 20. As shown in Fig. 1, the head is clamped to the upper end of the section 19 by one or more set screws 24, similar screws also being used to clamp said tubing to the tubular portion 21 of the base fitting 20.

10] A pipe 25 has its upper threaded end 26 connected with a threaded socket 27 in the bottom wall of the head and at its lower end to a guide plate 28 disposed adjacent the lower end of the tubing 19.

The head 18 has a cavity 30 formed therein which, as shown in Figs. 1 and 3, connects with an overhead supply pipe 31 of tempered water leading to the central portion of said cavity.

For controlling the supply of water from the cavity 30 to each of the pipes 17, an operator-controlled valve mechanism is provided. Each valve mechanism includes a valve housing 32 in the form of an elbow fitting having threaded connection with the pipe 17 and with an opening 33 leading into the head 18. A valve seat and casing member 34 is mounted in a bore 35 in the housing 32 and is clamped against a shoulder 36 by a gland member 37, a packing 39 being interposed between said shoulder 36 and shoulder 30 formed by the reduction of the diameter of the lower end of said housing 32 and a stuffing box packing 39 being interposed between the gland member 37 and a disc 40 seating on the top of the casing member 34. The gland member 37 is clamped down onto the packing 39 by a flanged nut 41 having threaded engagement with the valve housing 32. The valve 42 has a composition head member 43 clamped to a stem 44 by a flanged washer 45 and nut 46. The stem works through the stuffing box formed by the parts 31, 39, and 40, and its exposed end has a collar 47 secured to it, and a spring 48 is interposed between said collar 47 and the member 31 to normally hold said valve against its seat 49 at the lower end of the housing 32 which has a series of openings 50 therein, any one of which may align with the opening 51 in the casing 32 which leads to the outlet with which the pipe 17 is connected.

Each valve 42 is operated by a lever 52 pivotally mounted at one end on a pivot pin 53 carried by the head 18 and provided with an adjustable tappet screw 54 intermediate its ends engageable with the exposed end of the valve and at its outer end provided with an aperture 55 through which a rod 56 passes, said rod provided with a pair of adjustable stop nuts 57 at its upper end, the lower of which engages said lever 52, said rod extending down through a guide opening 58 in the head, through the cen-

tral standard 19 and through a slot in the plate 28 and having a stop 60 at its end engaged by the forked end 61 of a bather-operated lever 62.

The lever 62 is formed by a pair of metal frame members or strips 63 which are joined together in closely spaced relation at their forward portions to form the forked ends 61 engaging said stop 60 and are spread out at their back ends and secured to a ring-shaped frame member 64 at points about two-thirds of the diameter of said member 64. The ring member 64 has a platform member 65 welded to it and of a size which permits the operator to shift his position from the front to the midportion or the rear portion of said platform, and said platform may, as indicated at 66 in Fig. 2, have its top surface roughened or a coating material providing a roughened surface applied thereto. This platform 65 is also welded to the tops of the spread portions of the strips 63.

For pivoting the lever 62 intermediate its ends a pair of oppositely disposed socket members 67 are secured to said lever by being welded to the sides of the ring 64 at a distance of about two-thirds of the diameter of said member 64 and back from the front of said ring or that part nearest to the standard 11. These socket members 67 engage with complementary projections 68 formed on studs 69 set into the concrete floor or part 70 forming the floor of the room in which the shower is located.

The forked end 61 of the lever 62 projects through a slot 71 in the tubular portion 21 of the member 20, and the bottom of this slot limits the extent of downward movement of the lever 62 and hence the extent of opening movement of the valve 42. The member 20 also is provided with a plurality of radially disposed drainage openings 72, so that the waste water may drain from the floor 70 into said fitting 20 and then into the drain pipe 23.

In order to prevent ready removal of the lever 62, a locking device is provided therefor comprising a bar 73 carrying at its lower end a pin 74 anchored in the floor 70 and its upper end provided with a slot 75 through which a bolt 76 carried by the lever 62 is loosely fitted, so that while the bar 73 does not interfere with the normal operation of the lever 62, it will prevent bodily removal of said lever.

The inner end of the lever 62, the rod 56, and the lever 52 are normally urged to an inoperative or raised position by a spring 77 interposed between the head 18 and the lever 52. In this position the upward movement of the lever 62 is limited by the upper end of the slot 71.

In those instances where the water supply is brought in from below the base of the shower, the supply connections may be formed as shown in Figs. 6 and 7 wherein a tempered water supply pipe 78 connects with an elbow 79 in a fitting 80 forming part of the drain pipe 81, said elbow fitting connected at its upper end with a pipe 83 which extends up through the fitting 20, the tubing section 19, and has a threaded connection at its upper end with an opening 84 which in this instance is provided in the boss 27 of the head 18, the upper supply opening to said head being closed off by a pipe plug 85. A plate 86 similar to the plate 28 is secured to the pipe 83 by a set screw 87, said plate having guide openings 88 therein for the valve-operating rods 56.

With the construction above described when the bather enters one of the compartments 10 and steps on or puts his weight on the platform

65 forwardly of the pivotal connections formed by the parts 67 and 68, the lever 62 will be depressed and hence the rod 56 and the valve-operating lever 52 moved downwardly against the action of the spring 77, the screw 54 engaging the top of the valve stem 48 and pushing it downwardly to open the valve 42 and allow tempered water to pass from the head 18 to the pipe 17 and the shower head 16 for the compartment in which the bather is located, and the water is sprayed upon the bather positioned on the platform 65. Under these conditions the operator may move about on the platform 65, and the water will be supplied so long as the weight of the bather is applied by him forwardly of the pivot connections of the lever 62, it being noted that the depressed position of said lever is limited by the bottom of the slot 71 and brings the platform to a substantially level position. If while the bather is on the platform 65, he wishes to shut off the supply of water, all he has to do is to move or shift his weight to the outer end portion of the platform, that is, to the part to the rear of the members 67, and then the lever 62 will be tilted upwardly to the normal inoperative position of said lever and the valve-operating parts as shown in Fig. 1. As soon as the bather steps off of the platform 65, the valve and its operating mechanism will be returned to a closed position. Thus the shower will only remain in use while the bather is on the platform 65 although it may, at any time the bather wishes, be stopped while the bather is on said platform.

Each compartment may have a foldable curtain 89 mounted on the frame 14.

It will also be understood that the partitions 12 may be omitted and that such an arrangement will provide bathing spaces under the substantially equal spaced shower heads.

I desire it to be understood that this invention is not to be limited to any particular form or arrangement of parts except in so far as such limitations are included in the claims.

What I claim as my invention is:

1. In a shower apparatus having a standard provided with a drain opening in its lower portion and a shower head carried by said standard, the combination of a water supply connection for said head mounted on said standard, a spring closed valve in said connection to control the flow of water to said head, and means for operating said valve comprising a pivoted lever projecting into said standard and limited in its movement by the walls thereof, said lever having a platform on which the bather stands while operating the valve.

2. In a shower apparatus having a hollow standard rising from the floor and provided with a floor drain opening in its lower portion and a shower head carried by said standard for directing water toward the floor, the combination of a water supply fitting at the upper end of said standard, a connection from said supply fitting to said head, a spring closed poppet valve for controlling passage of water through said connection, a pivoted lever mounted on said fitting and engageable with said valve, a pivoted lever under said head projecting into said standard and provided with a platform on which the bather stands, and a rod extending up through said standard and operatively connecting said last named lever with the lever engageable with the valve.

HOWARD A. MULLETT.
